UNITED STATES PATENT OFFICE.

CLAYTON L. DAY, OF CHICAGO, ILLINOIS, ASSIGNOR TO CHICAGO BRIDGE & IRON CO.,
A CORPORATION OF ILLINOIS.

AUTOMATIC VENT FOR BREATHER ROOFS.

Application filed December 23, 1927. Serial No. 242,236.

This invention relates to improvements in automatic vents for "breather" roofs, and more especially to a vent for a roof of this kind used in connection with the storage of 5 gases and volatile oils.

For example, containers for volatile oils frequently are provided with movable roofs in order to permit changes in volume in the vapor space above the liquid. There is usually a limit to the range of movement of 10 such roofs, and consequently means must be provided for venting the tank when the roof reaches its maximum height.

One of the features of my invention is the 15 provision of such automatic venting means for use in connection with roofs of this character which is simple and efficient in operation and does away with mechanical valves, and the like.

20 Other features and advantages of my invention will appear more fully as I proceed with my specification.

In that form of device including the features of my invention shown in the accompanying drawings, Figure 1 is a vertical sectional view showing my invention applied to a breather roof of the type having its edge permanently attached to the shell, the central portion of said roof adapted to 25 move upwardly and downwardly, Fig. 2 is a similar view showing the invention embodied in connection with the breather roof of that type in which the entire roof moves bodily upwardly and downwardly, Fig. 3 is a view similar to Fig. 1 showing a modified form, and Fig. 4 shows another modification.

In that form of device embodying the features of my invention shown in the accompanying drawings, 10 indicates the usual cylindrical shell or wall of the tank and 11 the bottom, in the form shown in Fig. 1 the roof 12 is of the breather type with its outer edge 12^a permanently attached to the upper edge of the shell 10. The central portion of the roof 12 is adapted to move upwardly and downwardly in accordance with variations in volume in the vapor space 13 above the liquid 14 in the tank. The lowermost 45 position of the roof 12 is shown by the solid lines and the uppermost position by the broken lines.

Obviously, when the roof 12 reaches its maximum height as shown by the broken 50 lines in Fig. 1, the gas pressure must be

vented. I provide automatic means for doing this consisting of the cup 15 which may be mounted in any suitable manner, for example, on a post 16. The cup 15 is filled with a suitable liquid 17 and the roof 12 carries a vent pipe 18 with its upper end as indicated by 18^a projecting a sufficient distance above the roof 12 to give the desired internal maximum gas pressure. The lower end of the pipe 18 as indicated by 18^b is immersed in the liquid 17 in the cup 15. The parts are so proportioned that when the roof 12 reaches its maximum height or the top of its breathing movement the lower end of the pipe 18^b will be lifted out of the liquid in the cup thus losing the head of liquid in the pipe and venting the internal pressure.

In that form of device shown in Fig. 2, the breather roof is of a somewhat different 75 type and is here shown as a conical roof 112 adapted to rise and fall bodily. A liquid seal is provided at the edge of the roof comprising the cup with the liquid 21, the roof being provided with a depending flange 22 80 with its lower edge immersed in the liquid. The venting means is substantially the same and includes a cup 115 similar to the cup 15 with a vent pipe 118 similar to the vent pipe 18. The cup 115 is provided with liquid 117 and the lower end of the vent pipe 118 is immersed in this liquid. The parts are so proportioned that as the roof reaches its maximum height the end of the pipe 118 85 will be lifted out of the liquid to vent the 90 pressure.

The form shown in Fig. 3 is substantially the same as that shown in Fig. 1 except that the cup 215 corresponding to the cup 15 is raised in order to permit a higher level of 95 liquid in the tank. It will be seen that in the form shown in Fig. 1, the liquid in the tank cannot be higher than the top of the cup 15. If it should be higher than this the lower end of the vent pipe would not come 100 out when the roof reaches its maximum height. In the form of means shown in Fig. 1, therefore, the liquid must never be higher than the cup 15. The means shown in Fig. 3 permits a higher level of liquid in the tank 105 by raising the cup to a higher level. With the cup thus raised, means must be provided to permit the roof 212 to descend to its lowest position without striking the top of the cup. This is accomplished by providing the 110

roof with a raised portion 212^a to accommodate the cup in its lower positions. In the device shown in Fig. 3, the vent pipe is indicated by 218 and it is to be understood that 5 the general construction and operation is substantially the same as in the other forms.

A cover 30 may be provided over the top of the vent pipe to prevent rain from entering. In the form shown in Fig. 3 there is 10 indicated a maximum liquid overflow pipe 31.

The vent pipe, as indicated by 318, may be vertically adjustable by threading the same in the collar 319 on the roof 312.

15 While I have shown and described certain embodiments of my invention, it is to be understood that it is capable of many modifications. Changes, therefore, in the construction and arrangement may be made without 20 departing from the spirit and scope of the invention disclosed in the appended claims, in which it is my intention to claim all novelty in my invention as broadly as possible in view of the prior art.

25 What I claim is new, and desire to secure by Letters Patent, is:

1. In combination with a container having a breather roof of the character described; a stationary cup with a liquid; and a vent 30 pipe carried by the roof and adapted to move up and down with the roof in its breathing movement, the upper end of said pipe open to the atmosphere and its lower end immersed in the liquid in the cup and 35 adapted to be lifted out of said liquid upon the roof reaching substantially the top of its breathing movement.

2. In combination with a container having a breather roof of the character described; a stationary cup with a liquid, the 40

top of said cup being substantially level with the maximum oil level in the container; a raised portion in the roof adapted to accommodate the cup in the lower positions of the roof; and a vent pipe carried by the 45 roof and adapted to move up and down with the roof in its breathing movement, the upper end of said pipe open to the atmosphere and its lower end immersed in the liquid in the cup and adapted to be lifted out of said liquid upon the roof reaching substantially the top of its breathing movement.

3. In combination with a container having a breather roof of the character described; a stationary cup with a liquid; and a vent 55 pipe carried by the roof and adapted to move up and down with the roof in its breathing movement, the upper end of said pipe extending above the roof and open to the atmosphere and its lower end immersed 60 in the liquid in the cup and adapted to be lifted out of said liquid upon the roof reaching substantially the top of its breathing movement.

4. In combination with a container having 65 a breather roof of the character described; a stationary cup with a liquid; a vent pipe carried by the roof and adapted to move up and down with the roof in its breathing movement, the upper end of said pipe open 70 to the atmosphere and its lower end immersed in the liquid in the cup and adapted to be lifted out of said liquid upon the roof reaching substantially the top of its breathing movement; and means for adjusting the 75 vent pipe vertically with respect to the roof.

I witness whereof, I have hereunto set my hand this 12th December, 1927.

CLAYTON L. DAY.
